UNITED STATES PATENT OFFICE.

SAMUEL HEARONEMUS, OF SNOVER, MICHIGAN.

SCREW DRIVER.

Application filed March 5, 1923. Serial No. 622,915.

To all whom it may concern:

Be it known that I, SAMUEL HEARONEMUS, a citizen of the United States, residing at Snover, in the county of Sanilac and 5 State of Michigan, have invented a new and useful Screw Driver, of which the following is a specification.

This invention relates to screw drivers, and more particularly to the screw holding 10 type in which the screw is lifted after being removed.

The object of the invention is to provide a simply constructed, cheap, strong device of this character which may be readily manipulated.

With the foregoing and other objects in view which will appear as the description proceeds, the invention resides in the combination and arrangement of parts and in 20 the details of construction hereinafter described and claimed, it being understood that changes in the precise embodiment of the invention herein disclosed may be made within the scope of what is claimed without departing from the spirit of the invention.

In the accompanying drawings:—

Figure 1 represents a side elevation of a screw driver constructed in accordance with this invention shown applied;

Fig. 2 is a similar view taken in a plane at right angles to Fig. 1; and

Fig. 3 is a transverse section through the body member of the tool.

In the embodiment illustrated, the tool 35 constituting this invention comprises a body member 1 which is here shown cylindrical and of uniform diameter throughout, being provided at its front end with a screw engaging point or blade 2 and equipped in its opposite faces at a point spaced from said 40 end with longitudinally extending grooves 3 and 4.

This body member 1 may be equipped with any suitable form of handle 5 composed 45 of wood or other material.

The screw-holding device which constitutes a part of the invention comprises a sleeve 6 which encircles and is slidably mounted on the body 1 and is equipped with 50 rearwardly extending longitudinal fingers 7 and 8 having inturned lips 9 at their rear ends which enter grooves 3 and 4 said grooves forming guides for said fingers and holding the sleeve against turning on the body 1.

This sleeve 6 is provided at its front end 55 with longitudinally extending fingers 10 and

11 provided at their free ends with inturned lips 12 which engage the shoulders 13 formed at the base of the kerf-engaging blade 2 and limit the rearward movement of 60 the sleeve.

A coiled spring 14 encircles the body 1 with one end engaging the fingers 7 and 8 and its other end secured to the member 1 in any suitable manner and exerts its tension to force the screw holder 6 backward so that when the lips 12 of the front fingers 10 and 11 are engaged with the beveled head H of the screw S, the screw will be held 70 between said lips and the blade 2 which is inserted in the kerf of the screw so that the screw may be lifted out when removed, and will be held by the screw driver until manually released.

In the use of this screw driver, the screw holding device 6 is moved forwardly against the tension of spring 14 a sufficient distance to operate the lips 12 of fingers 10 and 11 to receive between them and the blade 2 the head H of the screw which is engaged by slipping these fingers sidewise over said head. The blade 2 is inserted in the kerf of the screw and the turning of the screw driver will operate to unscrew the screw, which may be lifted out of its socket by the 85 holder 6. This tool may also be used for inserting a screw, it having been first engaged by slipping the leaves 12 over the head and screwing the screw into place.

Various changes in the form, shape, proportion and other minor details of construction may be made without departing from the principle or sacrificing any of the advantages of the claimed invention.

I claim:—

A tool of the class described comprising a body member having diametrically opposite longitudinally extending grooves therein with a kerf-engaging blade at its front end having shoulders at its base, a screw holder in the form of a sleeve snugly fitting said body and slideable thereon and having rearwardly extending fingers with lips at their free ends engaging said grooves whereby the holder is held against turning on the body, and an intermediate offset portion embracing a coiled spring on said body to hold the sleeve normally in retracted position, longitudinally extending fingers at the front of said sleeve, said fingers being in alignment with said first mentioned fingers and having inturned lips at their

free ends to cooperate with said blades to clampingly clamp the head of the screw between them forming a three point screw holder, said lips engaging the shoulders at 5 the base of said blade when the sleeve is in retracted position with the fingers fitting closely against the body member.

In testimony that I claim the foregoing as my own, I have hereto affixed my signature in the presence of two witnesses.

SAMUEL HEARONEMUS.
